TUYÈRE

William V. Sauter, Philadelphia, Pa., assignor to
American Engineering Company, Philadelphia,
Pa., a corporation of Pennsylvania

Application February 27, 1935, Serial No. 8,572

9 Claims. (Cl. 110—44)

This invention relates to tuyères, and more particularly to the tuyère blocks employed in stoker furnaces.

During operation of a furnace thin spots often occur in the fuel bed which result in decreasing the resistance to the flow of air through the tuyères disposed therebeneath. This reduction in resistance causes the velocity of the air flowing through such tuyères to increase to such an extent that the fuel is often blown from the grates and as a result damage to the grates not only occurs but the effective area of the fuel bed is materially reduced. The heavier portions of the fuel bed under such conditions are also deprived of some of the air necessary to insure complete combustion.

One object of the present invention is to construct a tuyère block in such a manner as to reduce to a minimum the above mentioned difficulties.

Another object is to provide a tuyère block wherein the means thereon defining air passages are so disposed that the velocity of the air flowing therethrough decreases as it approaches the discharge end of said block.

Another object is to provide air passage defining means on each tuyère block in such a manner that the air passing therethrough is evenly distributed over the entire discharge end thereof.

A more specific object is to provide a tuyère block with a restricted inlet opening and to provide a series of relatively narrow passages leading therefrom, which passages diverge toward the discharge end of said block so that the velocity of the air discharging therefrom will be relatively low.

Other and further objects will become apparent as the description of the invention progresses.

Of the drawing:

Fig. 1 is a perspective view of the tuyère block in inverted position showing the arrangement of the air passages provided therein.

Fig. 2 is a plan view of the tuyère block shown in Fig. 1.

Fig. 3 is a sectional side view taken on line 3—3 of Fig. 2, and

Fig. 4 is a side elevational view of two tuyère blocks in assembled position.

Referring to the drawing, the numeral 1 indicates generally a tuyère block which in the present instance consists of a substantially flat body portion 2, having a rounded and slightly beveled nose portion 3. The under side of the tuyère block has provided at the sides thereof a pair of substantially vertical supporting portions 4 and 5,

the forward or as shown, the right hand end of each of which terminates in a beveled portion 6, which, in assembly on a stoker, rests upon the side plates of the retorts in a well known manner. The rear or left hand ends of portions 4 and 5 terminate substantially midway between the front and rear ends of the tuyère block, and the inner surfaces 7 and 8, respectively thereof, are substantially arcuate in form. A pair of ribs 9 diverge forwardly from a point 10 near the rear end of the tuyère block substantially on the longitudinal center line thereof. Ribs 9 terminate at the forward ends thereof in a semicircular rib 11 and form therewith a substantially stream line abutment to the incoming draft air. A cross rib 12 also extends between and connects the ends of rib 11 for the purpose of reinforcing the structure. Extending between ribs 9 and the inner arcuate portions 7 and 8 of members 4 and 5 are a series of alternately disposed long and short ribs 13 and 14, respectively. As shown in Figs. 1 and 2, these ribs are relatively wide at the forward ends thereof and gradually taper off toward the rear. By this construction the various air passages defined by these ribs are narrow or constricted at the inlet ends thereof and diverge toward the rear so that their discharge ends are relatively wide. A locking hook 15 is provided intermediate the ends of the tuyère block and between ribs 9, and a substantially rectangular slot 16 is provided slightly to the rear of said hook. In assembly the hook 15 of each tuyère block engages the end of the rectangular slot 16 of the next lower tuyère block of the series, as shown in Fig. 4. The hook 15 of each tuyère block being disposed in the dead space between ribs 9 is out of the path of the incoming draft air and thus prevents the formation of eddy currents. Air leakage between the tuyères through slots 16 is also prevented since these slots communicate with the dead spaces defined by ribs 9, 11 and 12. The lower surfaces of elements 4 and 5, and of ribs 9, 11, 12, 13 and 14, lie substantially in the same horizontal plane and when assembled on the stoker engage the upper flat surface of the next lower tuyère block of the series as shown in Fig. 4.

It will be noted that the inner arcuate surfaces 7 and 8 of side portions 4 and 5 form with ribs 9 and substantially semi-circular rib 11, a pair of throats 17 of substantially Venturi form. The forward ends of each of the ribs 13 and 14 are also of rounded construction so that the air inlet ends of the passages defined by said ribs are also of substantially Venturi form. Thus a

series of highly efficient passages for draft air are provided in each tuyère block. The arrangement of the long and short ribs 13 and 14 effectively subdivides the inlet passages 17 into a series 5 of separate passages whereby the incoming draft air is evenly distributed over the entire discharge end of each tuyère block, thus insuring efficient combustion of the fuel.

It is also apparent that the diverging construction of the air passages on each tuyère block toward the discharge end thereof effects a reduction 10 in the discharge velocity of the air passing therethrough and as a result the tendency for blow holes to occur, especially at the thin portions 15 of the fuel bed, is greatly minimized. Thus by preventing blowing of the fuel from such thin portions the fuel feeding mechanisms will be given the opportunity to build them up until they become normally uniform again before damage occurs 20 to the grates. Damage to the grates, and also uneconomic operation of the furnace due to such blow holes are therefore reduced to a minimum by the present construction and as a result a material saving is effected in the operating cost 25 of the furnace.

While the embodiment herein shown is admirably adapted to fulfill the objects primarily stated, it is to be understood that the invention is not to be limited to the said embodiment since it may 30 be embodied in other forms, all coming within the scope of the claims which follow.

What is claimed is:

1. A tuyère block, comprising a relatively flat body portion having when in operative position a substantially rounded rearwardly disposed discharge end, a pair of supporting members depending from the lower surface of said body portion at the opposite sides thereof, each of said supporting members having a vertically disposed 35 arcuate inner surface, a pair of ribs diverging forwardly from a point near the rearmost end of said discharge end and a substantially rounded rib near the forward end of said body portion connecting the forwardly disposed ends of said first mentioned ribs and forming a substantially stream line abutment for the incoming draft air, and said ribs forming with the arcuate inner surfaces of said supporting members, a pair of air 40 passages of substantially Venturi form.

2. A tuyère block, comprising a relatively flat body portion having when in operative position a substantially rounded rearwardly disposed discharge end, a pair of supporting members depending from the lower surface of said body portion at opposite sides thereof, each of said supporting members having a substantially vertically disposed arcuate inner surface, a pair of ribs diverging forwardly from a point near the rearmost end of said discharge end, a substantially 45 rounded rib near the forward end of said body portion connecting the forwardly disposed ends of said first mentioned ribs and forming a substantially stream line abutment for the incoming draft air, said ribs forming with the arcuate inner surfaces of said supporting members a pair of air 50 passages of substantially Venturi form, and a plurality of ribs extending longitudinally of said body portion between said arcuate members and said first mentioned ribs, said last mentioned ribs subdividing said air passages into a series of smaller 55 passages whereby the air flowing through said passages is evenly distributed over the entire discharge end of said tuyère block.

3. A tuyère block, comprising a relatively flat body portion having when in operative position

a substantially rounded rearwardly disposed discharge end, a pair of supporting members depending from the lower surface of said body portion at the opposite sides thereof, each of said supporting members having a vertically disposed 5 arcuate inner surface, a pair of ribs diverging forwardly from a point near the rearmost end of said discharge end, a substantially rounded rib near the forward end of said body portion connecting the forwardly disposed ends of said first mentioned ribs and forming a substantially stream line abutment for the incoming draft air, said ribs forming with the arcuate inner surfaces of said supporting members a pair of air passages of substantially Venturi form, and a locking hook on 10 said body portion disposed between said ribs.

4. A tuyère block, comprising a relatively flat body portion having when in operative position a substantially rounded rearwardly disposed discharge end, a pair of supporting members depending from the lower surface of said body portion at the opposite sides thereof, each of said supporting members having a vertically disposed 15 arcuate inner surface, a pair of ribs diverging forwardly from a point near the rearmost end of said discharge end, a substantially rounded rib near the forward end of said body portion connecting the forwardly disposed ends of said first mentioned ribs and forming a substantially stream line abutment for the incoming draft air, said ribs forming with the arcuate inner surfaces of said supporting members a pair of air 20 passages of substantially Venturi form, and a locking hook on 25 said body portion disposed between said ribs.

5. A tuyère block, adapted for arrangement 30

with similar tuyère blocks in superimposed 35 stepped relation, comprising a relatively flat body portion having when in operative position a substantially rounded rearwardly disposed discharge end, a pair of supporting members for said body portion depending from the lower surface at the opposite sides thereof, each of said supporting members having a substantially vertically disposed arcuate inner surface, a pair of ribs diverging forwardly from a point near the rearmost end of said discharge end, a substantially rounded rib near the forward end of said body portion, connecting the forwardly disposed ends of said first mentioned ribs and forming a substantially stream line abutment for the incoming draft air, said ribs in assembly providing a substantially dead space therebetween, a locking hook disposed between said ribs adapted in assembly to interlock with the next lower tuyère 40 block of the series, and said ribs forming with 45

the arcuate inner surfaces of said supporting members a pair of air passages of substantially Venturi form, and a plurality of ribs extending longitudinally of said body portion between said arcuate members and said first mentioned ribs and arranged in diverging relation toward said discharge end, said last mentioned ribs also having substantially rounded end portions subdividing said air passages into a series of smaller 10 passages whereby the air flowing through said passages is evenly distributed over said discharge end, and the lower surfaces of all of said ribs and supporting members lying in substantially the same horizontal plane and adapted in assembly to engage the upper surface of the next lower tuyère of the series.

6. A tuyère block comprising a relatively flat body portion, having an air inlet end and an air discharge end, a pair of projections extending 20 from one face of said body portion at the opposite sides thereof, said projections having substantially arcuate inner surfaces, a pair of ribs diverging toward said air inlet end from a point near the extreme end of said discharge end, a 25 substantially rounded rib provided intermediate the ends of said body portion, connecting the ends of said first mentioned ribs and forming a streamline abutment for the incoming draft air, and said ribs forming with the arcuate inner 30 surfaces of said projections a pair of air passages of substantially Venturi form.

7. A tuyère block comprising a relatively flat body portion having an air inlet end and an air discharge end, a pair of projections extending from 35 one surface of said body portion at the opposite sides thereof, said projections having substantially arcuate inner surfaces, a pair of ribs diverging toward said air inlet end from a point near the extreme end of said discharge end, a 40 substantially arcuate rib provided intermediate the ends of said body portion connecting the ends of said first mentioned ribs and forming a substantially streamline abutment for the incoming draft air, said ribs forming with the arcuate inner 45 surfaces of said projections a pair of passages of substantially Venturi form, and a plurality of ribs extending longitudinally of said body portion between said projections and first mentioned ribs, said last mentioned ribs subdividing said air passages into a series of

smaller passages, whereby the air flowing through said passages is evenly distributed over the entire discharge end of said tuyère block.

8. A tuyère block comprising a relatively flat body portion, having an air inlet end and an air discharge end, a pair of projections extending 5 from one face of said body portion at the opposite sides thereof, said projections having substantially arcuate inner surfaces, a longitudinally extending member disposed intermediate said projections, and forming therewith a pair of inlet 10 passages for draft air, the side edges of said last mentioned member diverging toward said air inlet end and terminating in a substantially arcuate portion whereby the said passages defined by said 15 longitudinally extending member and said projections have restricted throats of substantially Venturi form and diverging side walls, a hook projecting from said longitudinally extending member for securing the tuyère block in position, 20 a series of relatively long longitudinally disposed ribs provided between said longitudinally extending member and said projections dividing said 25 passages to a plurality of smaller passages, and a second series of shorter ribs interspersed with said first mentioned ribs subdividing said last 30 mentioned passages into a series of smaller passages, and the ends of all of said ribs extending toward the inlet end of said tuyère block being of enlarged construction and tapering toward 35 said discharge end, whereby the passages defined thereby have restricted throats and diverging side walls.

9. A tuyère block comprising a relatively flat body portion, having an air inlet end and an air discharge end, a pair of projections extending 35 from one face of said body portion at the opposite sides thereof, said projections having substantially arcuate inner surfaces, a pair of ribs diverging toward said inlet end from a point near 40 the extreme end of said discharge end, rib means provided intermediate the ends of said body portion connecting the ends of said first mentioned ribs, said ribs and the arcuate inner surfaces of said projections defining a pair of passages for 45 draft air, and a plurality of ribs extending longitudinally of said body portion between said projections and first mentioned ribs, said last mentioned ribs subdividing said first mentioned passages into a series of smaller passages.

50 WILLIAM V. SAUTER.
